STRAIGHTEDGE TOOL

William B. Petree, San Francisco, Calif.

Application April 14, 1937, Serial No. 136,853

9 Claims. (Cl. 164—73)

This invention relates to improvements in straight edge tools, and has special reference to cutting guides particularly designed for the use of paper hangers in trimming strips of paper.

5 An object of my invention is to provide an improved straight edge tool of the character described which is of light weight and particularly designed to maintain its accurate and straight condition regardless of changes in temperature 10 or climate and regardless of the rough usage to which such tools are ordinarily subjected.

Other or further objects of my invention will be pointed out hereinafter, indicated in the appended claims, or obvious to one skilled in the 15 art upon an understanding of the present disclosure. For the purposes of this application I have elected to show herein certain forms of a paper hanger's straight edge representative of my invention; it is to be understood however 20 that the embodiments of my invention herein shown and described are for purposes of illustration only, and that therefore they are not to be regarded as exhaustive of the variations of the invention, nor are they to be given any interpretation such as might have the effect of 25 limiting the claims short of the true and most comprehensive scope of the invention in the art.

In the accompanying drawing:

Fig. 1 is a fragmentary perspective sectional view of a straight edge tool embodying what I consider the preferred embodiment of my invention;

Figs. 2, 3, 4, 5 and 6 are similar views showing modified forms of my invention.

35 Referring to the drawing and particularly to Fig. 1, the numeral 1 designates an elongated body, substantially I-shaped in cross section and made preferably from a suitable light weight metal possessed of considerable strength and rigidity. Oppositely disposed lateral flanges 2 forming a part of the body 1 are disposed at true right angles with respect to said body.

Filters 3 and 4, of wood or other suitable light weight material are fitted within the channels formed at the opposite sides of the body 1 between the flanges 2.

45 Fitting over the flanges 2 of the elongated body 1 are metal facing members 5 and 6 having inwardly protruding flanges 5' and 6', respectively, 50 which firmly engage with the filters 3 and 4 and thereby maintain them in fixed positions with respect to the said body member. The facing members 5 and 6 being in firm engagement with the flanges 2 throughout their lengths, are normally maintained in fixed positions with respect

5 to the body member 1, or if so desired any other suitable means may be employed to prevent the shifting of the said facing members upon the flanges. It will be seen that the various parts comprising the straight edge tool may be readily assembled by first placing the filters 3 and 4 within the channels formed at the opposite sides of the body 1, and then slipping the facing members in place upon the flanges 2. The facing members 5 and 6 are each substantially block 10 C-shaped in cross-section with the longitudinal opening therethrough being of sufficient size to accommodate the lateral flanges 2 of the body 1. The upper sides of the facing members 5 and 6 lie in a common plane, while their lower sides also 15 lie in a common plane which is preferably parallel to the first mentioned plane. The outwardly disposed sides of the facing members 5 and 6 are each disposed at right angles to its upper and lower sides. The metal of each of the said facing members at the exposed right angle corners where the vertical side joins the horizontal sides is smooth and straight, thereby presenting a true and accurate guide for a cutter. The upper side 20 of the facing member 5 extends inwardly 25 throughout its length to provide a straight track or guide 7 for maintaining a paper cutting tool of the kind now commonly used by paper hangers, in its proper operating position. The lower sides of the facing members 5 and 6 offer considerable resistance to movement over a supporting surface, thereby facilitating the holding of the tool in a desired position. The lateral flanges 2 of the elongated body 1 give the latter considerable rigidity, and serve as suitable means for 30 mounting the facing members 5 and 6. The lateral flanges 2 not only give the desired rigidity to the body 1 but they provide suitable channels on opposite sides of the said body for the mounting and maintenance of the filters 3 and 4. 35

The embodiment of my invention shown in Fig. 2 is the same as that shown in Fig. 1, except that the guide or track 7 extending from the upper side of the facing member 5 is eliminated.

40 In the modified form of my invention shown in Fig. 3 an elongated metal body 1a is formed at its lateral side edges with right angle flanges 2a and with outwardly curved longitudinally disposed re-enforcing members 8. The re-enforcing members are joined to the lower flanges 2 50 and to the body member 1a near the latter's side edges, thereby providing a sturdy and rigid construction adapted to adequately brace the said flanges and the body member. Fitting over the flanges 2a are facing members 5a and 6a of the 55

kind previously described. The facing member 5a is provided with a longitudinally disposed track or guide 1a at its upper side for maintaining a paper cutting tool in its proper operating position.

The embodiment of my invention shown in Fig. 4 is the same as that shown in Fig. 3 except that the track or guide 1a extending from the upper side of the facing member 5a is eliminated.

10 In the modified form of my invention shown in Fig. 5 an elongated metal body 1b is formed at its lateral side edges with right angle flanges 2b and with upwardly and downwardly disposed projections 9 which extend longitudinally in parallel 15 relation to the said flanges. The longitudinally disposed projections are separated by a suitable groove within which the inwardly disposed flanges 5' and 6' of facing members 5b and 6b are adapted to fit. The longitudinally disposed projections 20 have inwardly disposed flanges 9' which form suitable means for maintaining fillers 3b and 4b in place against the upper and lower surfaces of the metal body 1b. The facing members 5b and 6b are of the kind previously described and the 25 former is provided with a longitudinally disposed track or guide 7b at its upper side for maintaining a paper cutting tool in its proper operating position. The filler 4b is preferably cut away at 30 points opposite the track 1 so as to permit the convenient use of the cutting tool in the manner intended.

The embodiment of my invention shown in Fig. 6 is the same as that shown in Fig. 5 except that the track or guide 7b extending from the upper 35 side of the facing member 7b is eliminated.

In the various modified embodiments of my invention the metal body is constructed from a suitable light weight material possessed of considerable strength and rigidity. In the forms 40 wherein the fillers are used the metal body is substantially encased by the facing members and the said fillers, thereby providing a structure wherein the body member is insulated and is not likely to be affected or distorted by changes in 45 the temperature of the surrounding air.

Having described my invention what I claim is:

1. A straight edge tool comprising an elongated body member substantially I-shaped in cross section having a central portion and lateral flanges, 50 and a filler positioned on at least one side of the body, and facing members fitting on the flanges.

2. A straight edge tool comprising an elongated body member substantially I-shaped in cross sec-

tion and longitudinally disposed facing members fitting over the lateral edges of the body member.

3. A straight edge tool comprising an elongated body member substantially I-shaped in cross section having a central portion and laterally disposed flanged portions, and facing members fitting over the flanges, the said facing members being substantially block C-shaped in cross section. 5

4. A straight edge tool comprising an elongated body member substantially I-shaped in cross section, longitudinally disposed facing members fitting over the lateral edges of the body member, and an inwardly disposed flange on one of the facing members for guiding a cutting tool. 10

5. A straight edge tool comprising an elongated body member substantially I-shaped in cross section, longitudinally disposed facing members fitting over the lateral edges of the body member, and fillers located on opposite sides of the body 15 20 member.

6. A straight edge tool comprising an elongated body member substantially I-shaped in cross section having a central portion and lateral flanges, a longitudinally disposed filler on at least one side 25 of the body member, and longitudinally disposed facing members fitting over the flanges and in engagement with the filler.

7. A straight edge tool comprising an elongated body member, lateral flanges formed on the body 30 member, enlarged re-enforcing portions at one side which are joined to certain of the flanges and to the said body member, and facing members fitting over the flanges.

8. A straight edge tool comprising an elongated body member, lateral flanges formed on the body member, enlarged re-enforcing portions formed at the juncture of certain of the flanges and the body member, facing members fitting over the flanges, and an inwardly disposed flange on one 40 45 of the facing members for guiding a cutting tool.

9. A straight edge tool comprising an elongated body member, lateral flanges formed on the body member, protruding members formed on the body member in parallel relation to but separated from the flanges, fillers positioned on the opposite faces of the body member between the protruding members, flanges on the protruding members for holding the fillers against the body member, and facing members fitting on the lateral flanges 50 55 of the body member.

WILLIAM B. PETREE.
